UNITED STATES PATENT OFFICE.

ALEXANDER G. MORRISON AND OSCAR GOTSCHE, OF ST. LOUIS, MISSOURI.

ADJUSTABLE CHAIN PORTIÈRE, VALANCE, OR GRILLE.

1,057,491.

Specification of Letters Patent.

Patented Apr. 1, 1913.

Application filed March 28, 1912. Serial No. 686,947.

To all whom it may concern:

Be it known that we, ALEXANDER G. MORRISON and OSCAR GOTSCHE, citizens of the United States, and residents of St. Louis, Missouri, have invented certain new and useful Improvements in Adjustable Chain Portières, Valances, or Grilles, of which the following is a specification containing a full, clear, and exact description, reference being 10 had to the accompanying drawings, forming a part hereof.

Our invention relates to an improved adjustable chain portière, valance or grille, and consists in the novel construction hereinafter shown and described, and claimed.

The object of our invention is to improve upon the construction disclosed in the prior patent granted to W. S. Hépburn and present joint applicant, Alexander G. Morrison, 20 dated July 15, 1902, No. 704,799.

A further object of our invention is to provide an improved adjustable chain portière, valance, or grille, with the improved pole links and the connections thereto, 25 whereby the device will produce a more artistic effect and at the same time be economical in cost as well as convenient and efficient in operation and use.

A further object of our invention is to 30 provide an improved loop for detachably connecting the ornamental balls, acorns and other bodies composing the pendants of the portière.

In the drawings, Figure 1 is a front elevation of our improved adjustable chain portière, valance or grille; Fig. 2 is a detail view of portions of the portière, parts being broken away to economize in drafting space; Fig. 3 is a detail sectional elevation 35 of one of the ornamental balls used in carrying out the invention; Fig. 4 is a detail, sectional elevation of a different form of ornament used in carrying out the invention; Fig. 5 is a full size view of a detachable connecting loop, used in connecting the ornamental bodies to the supporting hooks and chains; and Fig. 6 is a full size view of 40 one of the pole links in position upon the pole or rod.

Referring again to the drawings, 1 indicates a pole or rod preferably made of metal, tubular in cross section, and adapted to be fixed in position at the top of the opening, window or door in which the device is 50 to be hung. The said pole or rod 1 is adapt-

ed to be fixed in position by means of the usual supporting hooks and end sockets (not shown). Loosely mounted upon the pole or rod 1 is a series of metallic pole links 2 which are in the form of an ordinary chain link, with the exception that the upper or pole eye 3 is of greater diameter than the lower eye 4, and said eyes face in a direction at right angles with respect to each other. The said pole links 2 are slidingly mounted 60 upon the said pole or rod 1, and are connected by a series of chain links 5. Said chain links 5 hang loosely from the said pole links 2. Pendants, consisting of a series of ornamental balls 6, and ornamental 65 wooden bodies 7 terminating in acorn-shaped bodies 8, are suspended from said chain links 5 by means of additional chain links 5 and our improved detachable wire connecting loops 9. Said ornamental balls 70 6, ornamental wooden bodies 7 and acorn-shaped bodies 8 are also connected to each other in each pendant by means of additional chain links 5 and our detachable wire 75 connecting loops 9. Each of the ornamental 80 balls 6, ornamental wooden bodies 7 and acorn-shaped bodies 8 is provided with a central, axial, cylindrical bore 10 within which the said detachable wire connecting 85 loops 9 are detachably located and held by 90 frictional contact with the internal walls of the said cylindrical bore. Said loops 9 are preferably made of a single integral piece 95 of wire having portions 11 and 12 adjacent each end doubled back substantially parallel 100 to its body, (see Figs. 3, 4 and 5.) Said loops are preferably made of spring wire and the said portion 12 normally extends a greater distance from the body than does the portion 11, so that said portion 11 will 105 offer little or no obstruction to the passage of the loop into the cylindrical bore 10, but the portion 12 will spring outwardly and forcibly engage the walls of said bore and retain the loop within said bore.

In Figs. 3 and 4, we have shown the loops 110 preferably fixed within the ornamental bodies. The only difference in construction between the loops shown in Figs. 3 and 4 is that the one shown in the last mentioned figure has a greater length in order to extend completely through the bore of the longer ornamental body 7. The loops 9 may thus very properly be termed "spring loops".

The operation of our invention is obvious and therefore need not be further described, except to say that the device may be fitted to openings, windows or doors of any desired widths. On narrow openings, the pole links 2, of course, will be spaced closer together, while on wider openings they will be spaced farther apart.

It will, of course, be understood that the eyes 4 of the pole links may be opened and closed for connecting and disconnecting the chain links therewith, as it is also obvious that any of the chain links may be likewise manipulated for the purpose of connecting said links with each other, or with the loops 9.

The eyes 3 of the pole links 2 are preferably made of such size as to closely fit upon the pole or rod 1, and should they be a little too large they may be readily closed upon the pole or rod by means of a suitable tool, such as pliers, so that said links will retain their positions on the pole or rod by reason of the resiliency of the metal composing said links.

We claim:

The improved adjustable chain portière, valance, or grille construction, comprising a suspending rod or pole, pole links slidingly mounted on said rod, a series of chain links connecting said pole links, a detachable wire connecting-loop suspended from said chain links and having near the center of its length a laterally-projecting spring-locking portion, an ornamental body having an axial bore and detachably mounted upon said loop and forcibly held thereon by frictional contact with said projecting spring-locking portion of said loop within said bore, and additional ornamental bodies depending from the lower end of said loop, below said ornamental body.

In testimony whereof, we have signed our names to this specification, in presence of two subscribing witnesses.

ALEXANDER G. MORRISON.
OSCAR GOTSCHE.

Witnesses:

E. L. WALLACE,
JOHN C. HIGDON.
